UNITED STATES PATENT OFFICE.

JAMES RAYMOND O'BRIEN, OF CHICAGO, ILLINOIS.

ROAD MARKER.

Application filed September 10, 1925. Serial No. 55,455.

To all whom it may concern:

Be it known that I, JAMES RAYMOND O'BRIEN, a citizen of the United States, residing at Chicago, in the county of Cook and State of Illinois, have invented certain new and useful Improvements in Road Markers, of which the following is a specification.

This invention relates to improvements in markers, particularly adapted, though not necessarily limited in its use, in connection with vehicle traffic, and one of the objects of the invention is to provide an improved marker comprising a block or element having a flat surface with a letter or character thereon, a plurality of the blocks or elements being adapted to be placed in the pavement in proximity to each other and at or adjacent a crossing or intersection of streets or roads, so that the tops of the elements will be flush with the top of the pavement and will be clearly visible to the operator or driver of the vehicle and at the same time the marker will not form an obstruction to, or projection above the pavement.

A further object is to provide improved means for anchoring or securing the markers in position and in a manner to prevent accidental or unauthorized removal of the same.

A further object is to provide an improved marker of this character which may be readily placed in position in a pavement which has already been constructed or laid, or in a pavement which is under course of construction, and which marker is preferably formed of separate elements of such a construction that any one or more of the elements may be readily removed to permit renewal or replacement when worn or when desired.

To the attainment of these ends and the accomplishment of other new and useful objects as will appear, the invention consists in the features of novelty in substantially the construction, combination and arrangement of the several parts hereinafter more fully described and claimed and as shown in the accompanying drawings illustrating the invention and in which drawings:

Figure 1, is a top plan view illustrating intersecting street or road ways having sev-

eral of the markers, constructed in accordance with the principles of this invention in place in the pavement. 55

Figure 2, is an enlarged top plan view of one of the markers and a portion of the pavement. 60

Figure 3, is a vertical sectional view on line 3—3 Figure 2. 65

Figure 4, is a view similar to Figure 3 of another form of element and anchoring means therefor. 70

Figure 5, is a view similar to Figure 3 of another form of element and anchoring means therefor. 75

Figure 6, is a top plan view similar to Figure 2 of another form of the invention. 80

Figure 7, is a vertical sectional view on line 7—7 Figure 6. 85

Figure 8, is a perspective view of a detailed portion of the anchoring means shown in Figure 7. 90

Referring more particularly to the drawings and to the form of the invention shown in Figures 1 to 3, the numeral 10 designates generally a block or element of any desired size and configuration and constructed of any suitable material, preferably hard rubber or composition, a portion 11 of the element being preferably of a color contrasting with the color of the remaining portion of the element and being shaped to form or delineate a character or letter, the top of the character being flush with the top of the element and the entire upper surface of the element being preferably substantially flat. 95

The element thus formed may be produced in any suitable manner and is of a material which will withstand considerable wear. 100

Secured to the bottom of the element in any desired or suitable manner is an anchor plate or member 12 which is also constructed of any suitable material preferably of metal and is of a diameter considerably greater than the exterior diameter of the element 10 to form laterally projecting flanges disposed a considerable distance below the top of the element to form a base therefor and which flanges are continuous throughout the length of the respective adjacent upright surfaces of the block. 105

Anchor bolts 13 may be provided which extend through suitable openings in the base plate 12 to be embedded in the pavement,

and if desired transverse members such as pins or the like 14 may extend through the bolts 13 and assist in anchoring the marker element.

- 5 When this improved marker is to be incorporated in a pavement that is under course of construction, the elements may be assembled as shown in Figure 3 and placed in position after a sufficient amount of the 10 pavement has been laid to form a support for the element and upon which portion of the pavement the plate or member 12 rests with the anchor bolts 13 projecting downwardly into the pavement. The remaining 15 portion or surface 15 of the pavement is then placed and the plate 12 will also be embedded therein, the top surface being flush with the top of the element 10 and closely encompassing the element so that the latter 20 will be firmly set or embedded in the pavement, whereby the element will not only be prevented from accidental displacement but the edges and sides thereof will be protected against damage and against crumbling.
- 25 In the form of the invention shown in Fig. 4, the element 16 is of the same general construction as the element 10 with the exception that the peripheral walls 17 of the element are inclined or beveled downwardly 30 and inwardly from the top surface of the element so that the adjacent portion of the pavement 15 will co-operate with the inclined walls of the element to form a locking or additional anchoring means for the 35 element.

In Figure 5 the element 18 is also of the same general construction as the element 10 with the exception that the peripheral walls of the element 18 are inclined or beveled 40 downwardly and outwardly from the upper to the lower surface of the element to produce an additional anchorage or locking means for the element.

Obviously any form and number of anchoring bolts suitable for the purpose may be employed in connection with the anchoring plate 12.

In the form of the invention shown in Figures 6 to 8 the body of the element 19 is 50 preferably constructed in the same manner as the element 10 and the element 19 is secured to an anchor plate 20 preferably by means of angularly disposed lugs or projections 21 by embedding the lugs within the 55 body of the element preferably while the element 18 is being formed.

These lugs or projections are preferably formed by cutting out a portion of the plate 20 and then deflecting the cutout portions 60 to the desired shape, the material from which the element 19 is constructed will then fill the opening 22 in the plate 20 and the lugs will be firmly seated within the body of the element.

65 The plate 20 is of a diameter considerably

greater than the exterior diameter of the element 19 to form a laterally projecting circumferential flange encompassing the element and upon which flange the pavement or surface 23 will rest.

The periphery of the element 19 is provided with a circumferential groove or recess 24 intermediate and spaced from the top and bottom of the element and opens outwardly to receive a portion of the pavement or surface 23 as at 25, with the result that a key like locking portion will be produced which extends into the element 19 and assists in securing or anchoring the element in position.

70 Anchoring bolts 26 may also be provided which pass through the plate 20 and may be provided with split ends 27, and a block or wedge 28 may also be provided and so positioned that when the bolts 26 are placed in 85 position and the split ends forced over the block 28 the split ends will spread and will assist in anchoring the bolts.

80 By the provision of the laterally projecting flanges which are continuous throughout the 90 length of the adjacent upright faces of the block and upon which flanges the pavement rests, there will be provided means whereby the block will be anchored for yielding movement with the pavement. That is to 95 say, when the pavement yields under the weight of a load, especially in warm weather, the pressure of the pavement upon the anchor-plate will cause the block to be depressed with the pavement, to maintain the 100 upper face of the block at all times substantially flush with the upper surface of the pavement and as the pavement rises when the load is relieved therefrom the block and plate will also rise. Furthermore by providing flanges which are continuous throughout the length of the adjacent upright faces of the block, the block will be maintained against the tendency of a tilting action when a weight, such as of a heavy vehicle, strikes 110 one end or margin of the top of the block.

105 With this improved construction it will be manifest that an extremely efficient and durable marker will be provided and when in position may be readily seen by the operator of a vehicle and will be in a position not to form a projection or obstruction projecting above the pavement.

110 Furthermore the marker elements being separate may be readily removed and when 120 in position will be protected and firmly anchored and embedded in the pavement.

115 While the preferred forms of the invention have been herein specifically described it is to be understood that various changes 125 may be made in the details of construction and in the combination and arrangement of the several parts, within the scope of the claims, without departing from the spirit 130 of this invention.

What is claimed as new is:

1. A road marker embodying a block like body portion, the upper surface thereof being substantially flat, and an anchor plate upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 40
2. A road marker embodying a block like body portion, the upper surface thereof being substantially flat, an anchor plate upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 45
3. A road marker embodying a block like body portion, the upper surface thereof being substantially flat, an anchor plate upon which the block rests, the lower face of the block and the said plate being firmly secured together to constitute an integral structure, the said plate projecting beyond the block to form flanges continuous throughout the length of the respective adjacent upright surfaces of the block, said block and plate adapted to be embedded in the pavement so that the pavement will rest upon the said flanges and thereby anchor the block for yielding movement with the pavement, the top of the said block being maintained substantially flush with the surface of the adjacent portion of the pavement. 50
4. A road marker embodying a resilient block-like body portion, the upper surface thereof being substantially flat, and an anchor plate of a different and non-resilient material upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 55
5. A road marker embodying a block like body portion, the upper surface thereof being substantially flat, an anchor plate upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 60
6. A road marker embodying a block like body portion, the upper surface thereof being substantially flat, an anchor plate upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 65
7. A road marker embodying a block like body portion, the upper surface thereof being substantially flat, an anchor plate upon which the block rests, the lower face of the block and the said plate being secured together, the said plate projecting beyond the block to form flanges continuous throughout the length of the respective adjacent upright surfaces of the block, said block being adapted to be embedded in the pavement so that the pavement will rest upon the said flanges and thereby anchor the block for yielding movement with the pavement, the top of the said block being normally flush with the upper surface of the adjacent portion of the pavement. 70

In testimony whereof I have signed my name to this specification, on this 20th day of August, A. D. 1925.

J. RAYMOND O'BRIEN.
